UNITED STATES PATENT OFFICE.

WILMER C. GILMORE, OF BLOOMINGTON, ILLINOIS, ASSIGNOR TO UNIVERSAL VOTING MACHINE COMPANY, OF BLOOMINGTON, ILLINOIS, A CORPORATION OF MAINE.

SLIDE-MOVING DEVICE FOR VOTING-MACHINES.

No. 853,169.

Specification of Letters Patent.

Patented May 7, 1907.

Application filed February 16, 1906. Serial No. 301,483.

To all whom it may concern:

Be it known that I, WILMER C. GILMORE, a citizen of the United States, residing at Bloomington, in the county of McLean and State of Illinois, have invented certain new and useful Improvements in Slide-Moving Devices for Voting-Machines, of which the following is such a full, clear, and exact description as will enable others skilled in the

art to which it appertains to make and use my said invention.

My invention relates primarily to voting machines of that class which employ a series of perforated slides simultaneously movable and also adapted for independent setting, for the purpose of depositing balls, disks or equivalent counters selectively in ballot boxes or receptacles underlying said slides respectively. My improvements are however not strictly confined to voting machines, but may without material modification and without departure from my invention, be applied to other apparatuses such as cash registers, sales registers, or the like, employing movable parts, such as slides, capable of independent adjustment but which it is at times desirable to move simultaneously.

The purposes of my invention are to provide simple and effective means for simultaneously moving inward or outward a series of movable parts such as slides, said slide-moving device being adapted to permit separate adjustment of said slides relative to a co-operating depositing device such as a perforated dropping plate; to provide in connection with said slide moving device simple and effective means for operating said ball-depositing device; and to provide simple and effective means for operating stirrers in the ball hopper coincidently with the operation of the ball-dropping device, in order that at each movement of the ball-dropping device balls may be immediately supplied to fill all the empty chambers of the ball-dropping device preparatory to the next dropping.

With these ends in view my invention consists of the novel features of construction and combinations of parts shown in the annexed drawings to which reference is hereby made and hereinafter particularly described and finally recited in the claims.

Referring to the drawings in which similar reference letters and characters designate

like parts in the several views: Figure 1—is a top plan of a voting machine embodying my invention, only so much of the voting machine being shown as is necessary to illustrate the connection of my improvements therewith; Fig. 2—is a vertical section on the line 2. 2. of Fig. 1, and Fig. 3 is vertical section on a reduced scale, taken on the line 3. 3. of Fig. 1.

The mechanism is contained in a cabinet A which may be of any convenient form and of any suitable construction.

A series of slides B slide between guides B¹ supported on the plate A¹.

Each of the slides B has a perforation b which by proper setting of the slide may be caused to occupy a position transversely in range with a perforation a in the plate A⁴ and in register with a suitable perforation (not shown) in the top of the underlying ballot box or receptacle E.

Within the cabinet A is a hopper A³ adapted to contain a supply of balls to be used in voting. The bottom of the hopper consists of a plate A⁴ having a number of series of perforations a through which balls pass as hereinafter explained.

A dropping-plate D has a number of series of perforations d. The plate D is situated above the slides B and under the bottom A⁴ of the hopper A³. The plate D is slidable alternately to the right and left by means hereinafter described to cause the perforations d to alternately register with the perforations a in the bottom A⁴ and the perforations b in the slides B, so as to cause balls to pass from the hopper A³ through the perforations b in the slides B, into the ballot boxes E, where they remain until counted. Guide blocks F¹ are secured on suitable stationary supports F¹ on the inside of the cabinet. Parallel rods F² and F³ are slidable in the guides F.

Shafts G and G¹ are mounted to turn in bearings g on the walls of the cabinet. The judge's lever G² is secured on the shaft G. The voter's lever G³ is secured on the shaft G¹. Arms G⁴ are secured on the shaft G¹ and similar arms G⁵ are secured on the shaft G. A bar G⁷ secured at the ends of the rods F² extends across and is slidable above the slides B, and engages with upwardly projecting pins b¹ on the slides to simultane-

ously move all of the slides outward. Connecting rods G^8 connect the ends of the bar G^7 with the arms G^4 , so that when the lever G^3 is pulled forward the bar G^7 will travel forward and when the lever is pushed rearward the bar will travel rearward. A bar G^9 secured at the ends of the rods F^3 extends across and is slidable above the slides B and in its rearward travel, after the slides have been pushed forward by the bar G^7 , as already described, engages with the pins b^1 to simultaneously move all of the slides rearward. Rods G^{10} connect the ends of the bar G^9 with the arms G^5 , so that when the lever G^2 is pulled forward the bar G^9 will travel rearward and when the lever is pushed rearward the bar will travel forward.

An upwardly extending and laterally projecting pin f , secured on the left hand rod F^3 , engages with the inclined edge d^1 of the dropping plate D , to slide the plate to the right when the rod F^3 is slid rearward, and a similar pin f^1 , secured on the right hand rod F^1 , in like manner engages with the inclined edge d^2 , to move the plate D to the left.

When the plate is at rest in the position shown in Fig. 1 the holes d are in registry with the holes a in the bottom of the hopper, but are not in registry with the holes in the slides. When the plate D is in this position balls occupying the holes d will lie on top of the slides B , and the slides may be slid inward and outward at pleasure without the balls falling through the perforations in the slides. The slides B , being slidable longitudinally as already explained may be slid inward or outward at pleasure within the limits between the bars G^7 and G^9 , to cause the perforation b of each slide to occupy a position transversely in range with a perforation a in the plate A^4 and in register with a perforation in the top of the underlying receptacle E , and upon transverse movement of the plate D the balls in the corresponding holes d will fall through the perforations b respectively into the receptacles E , according to the setting of the slides; and the bodies of the slides being between the holes d and the perforations of the receptacles E will prevent the dropping of any of the balls contained in the holes d of the plate D except the balls which have entered the perforations b before the transverse movement of the plate D .

When the slides are adjusted at the pleasure of the voter as described, the holes b in the slides will be transversely in line with but not in registry with the holes d of the dropping plate D . If the judge's lever G^2 be then pulled forward it will cause the rods F^3 to slide rearward and cause the pin f to engage with the edge d^1 of the plate D , and move the plate to the right so as to bring the holes d of the plate into registry with the holes b of the slides and the balls contained

in the registering holes d , will fall through the holes in the slides into the underlying ballot boxes E . Reverse movement of the lever G^3 will produce reverse movement of the plate D , and cause the holes d to again fill with balls in readiness for the setting of the slides by the next voter, and so on as long as the voting continues.

The stirrers H are metal strips having longitudinal slots which accommodate screws h , connecting the stirrers with the plate A^4 , so that the stirrers may slide freely on the plate. The stirrers have screw threaded stems h^1 , and nuts h^2 , fitting on said stems. A cross bar H^1 , connects the stirrers so that they all move together.

A plate H^2 is secured on the side of and extends above the bar G^9 , and has notches h^3 , in which the stems fit loosely so that the bar may slide freely under the stems. When the judge's lever G^2 is pulled forward it causes the bar G^9 , to travel rearward carrying the plate H^2 , with it and causes the plate H^2 , to strike the nuts h^2 , and slide all of the stirrers rearward. Reverse movement of the lever causes the plate H^2 , to strike against the bar H^1 , thereby sliding all of the stirrers forward.

The travel of the stirrers may be shortened by turning the nuts h^2 on the stems h^1 , to shorten the distance between the plate H^2 , and the nuts h^2 .

I am aware that stirrers have been used in the ball-hoppers of voting machines I therefore do not broadly claim such use of stirrers but restrict my claim to the means whereby the stirrers are operatively connected with the dropping plate.

In practical use the voter, if he wishes to vote a straight ticket pulls the lever G^3 , forward, thereby moving all of the slides simultaneously into position to vote the straight ticket of his choice; or if he wishes to vote a mixed ticket, he sets the slides B , separately in position to deposit ballots for the candidates of his choice. After the voter has set all of the slides B , as he desires, he signals an authorized officer of the election, who in the voters presence, pulls the lever G^2 , to cause the plate D , to drop the balls through the holes in the slides respectively as set by the voter, into the underlying ballot boxes. The election officer then immediately pushes the lever G^2 , backward to cause return movement of the plate D , to its initial position and also to cause the stirrers to operate and cause a ball to enter every empty chamber of the plate D . The machine is then in readiness for use by the next voter, who in turn sets the slides as described; and so on as long as the voting continues.

Having fully described my invention what I claim as new and desire to secure by Letters Patent is.

1. A slide moving device comprising sta- 130

tionary guide blocks, parallel rods slidable in guides on said blocks, cross-bars connecting said rods in pairs, an upper shaft turning in stationary bearings, a lower shaft turning in stationary bearings, arms secured on said upper shaft, rods connecting said arms with one of said cross bars, arms secured on said lower shaft, rods connecting said last named arms with the other cross bar and slides 10 movable in one direction by one cross bar and movable in the opposite direction by the other cross bar.

2. A slide moving device comprising stationary guides, parallel rods sliding in said guides, cross bars connecting said rods in pairs, an upper shaft and a lower shaft turning in stationary bearings, arms secured on said upper shaft, rods connecting said arms with one of said cross bars, arms secured on 15 said lower shaft, rods connecting said last named arms with the other cross bar, slides 20 slidable under said cross bars and upwardly projecting pins on said slides between said cross bars.

25 3. The combination of stationary guides, rods slidable in said guides, a cross bar connecting said rods, a notched plate secured on

said cross bar, stirrers slidable in the notches of said plate, a cross piece connecting said stirrers, a hopper having a perforated bottom 30 on which said stirrers slide, a dropping plate 35 slidable transversely under said hopper and having inclined edges, also having perforations registerable with the perforations in the bottom of said hopper, and pins on said slideable rods engaging with the inclined edges of said dropping plate; all co-operating to cause longitudinal movement of said stirrers co-incidently with the transverse movement of said dropping plate. 40

4. In a slide moving device the combination of stationary guides, parallel rods slideable in the guides, a cross bar connecting the rods, slides having pins on which the cross-bar acts, an oscillative shaft, arms secured on 45 the shaft, and rods connecting the arms with the cross bar.

In witness whereof I have hereunto subscribed my name at Bloomington, Illinois this 14th day of November 1904.

WILMER C. GILMORE.
